(57) **CLAIM**

I claim the ornamental design for a gravy separator, as shown and described.

DESCRIPTION

FIG. 1 is a top view of a gravy separator;

FIG. 2 is a front view of the gravy separator;

FIG. 3 is a bottom view of the gravy separator;

FIG. 4 is a back view of the gravy separator;

FIG. 5 is a left side view of the gravy separator;

FIG. 6 is a right side view of the gravy separator; and,

FIG. 7 is a perspective view of the gravy separator.

The broken lines representing holes in FIGS. 1 and 7 are for the purpose of illustrating an environment and form no part of the claimed design.
